UNITED STATES PATENT OFFICE.

EDWARD C. SEEREITER, OF BUFFALO, NEW YORK.

TOY OR TOY WAGON.

No. 836,538.

Specification of Letters Patent.

Patented Nov. 20, 1906.

Application filed March 21, 1906. Serial No. 307,184.

To all whom it may concern:

Be it known that I, EDWARD C. SEEREITER, a citizen of the United States, and a resident of Buffalo, in the county of Erie and State of New York, have invented a new and Improved Toy or Toy Wagon, of which the following is a full, clear, and exact description.

The object of the invention is to provide a new and improved toy or toy wagon built of easily-separable pieces to allow a child to readily take the whole article apart and to re-unite the pieces and rebuild the article, thus furnishing means to keep the child occupied and at the same time serving as a medium for educational or manual-training purposes.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a longitudinal sectional elevation of the improvement in the form of a bus. Fig. 2 is an inverted plan view of the same. Fig. 3 is a plan view of the same. Fig. 4 is a rear end elevation of the same, parts being in 30 section, on the line 4 4 of Fig. 3; and Figs. 5 and 6 are perspective views of poles or tongues for the wagon.

The wagon-bed consists, essentially, of a bottom A, sides B B', a front C, and a rear D, 35 having a cut-out portion for permitting convenient ingress and egress to and from the wagon-body. On the top of the sides B B', the front C, and the rear D rest longitudinally-extending seats E E', having seat-backs F F', and on the top of the front C also rests a front seat G, extending between the inner opposite edges of the longitudinal seats E E'. A seat-back H for this front seat G extends between the seat-backs F F' and has a depending portion fitted between the inner edges of the longitudinal seats E E'. (See Fig. 4.) End pieces H³ rest on the top of the rear ends of the longitudinal seats E E'. On the front C is arranged a foot-rest I, and from the rear 50 end of the bottom A depends a sectional step J, leading to the opening formed in the rear D.

Now in order to fasten the several parts together they are provided with registering apertures for receiving bolts having nuts at 55 both ends to allow convenient insertion and removal of the bolts, as shown in the draw-

ings. Vertically-disposed bolts K unite the bottom A, the sides B B', the longitudinal seats E E', and the seat-backs F F' with each other. A transverse bolt K' connects the 60 sides B B' and the front C with each other. Bolts K² connect the sections of the step J with each other and also connect the step J with the bottom A and the rear D, and bolts K⁴ connect the foot-rest I to the front C. 65 The front seat-back H is preferably provided at its ends with tenons H', fitting corresponding mortises in the seat-backs F F', and the said tenons H' are engaged by dowel-pins H², passing vertically down in the seat-backs F 70 F'. The seat G is engaged by dowels G', extending through the seat-back H into the rear portion of the seat G, as will be readily understood by reference to Figs. 1, 3, and 4. The rear pieces H³ are provided with tenons 75 H⁴, engaging the seat-backs F F', and the said tenons H⁴ are engaged by dowel-pins H⁵, extending down through the seat-backs F F'. Thus by the arrangement described a child is readily enabled to take the entire wagon- 80 body apart and to reassemble the pieces whenever it is desired to do so and to fasten the same together.

The running-gear for the wagon-body is arranged as follows: On the under side of the 85 bottom A fit transversely-extending beams L, onto which is fastened by bolts K⁶ a plate L', the same bolts K⁶ also engaging the bottom A, as shown in Fig. 1. To the under side of the plate L' is bolted by bolts K⁷ a 90 front bolster L³, engaged by a king-bolt L⁴, also engaging the front axle N, carrying removable front wheels O. The front axle N is provided with suitable hounds N', engaged by a removable tongue or a pole P or P'. 95 (Shown in Figs. 5 and 6.) The king-bolt L⁴ is also engaged by the front end of a reach Q, fastened at its rear end by a bolt Q' to the under side of the bottom A. A rear bolster R is made in the form of two sets of sectional 100 longitudinal beams fastened by bolts K⁷ to the bottom A, and on the said bolster R is secured by bolts K⁸ a rear axle R', carrying rear wheels S.

From the foregoing it will be seen that the 105 several parts of the running-gear can be readily taken apart and reassembled whenever it is desired to do so.

Having thus described my invention, I claim as new and desire to secure by Letters 110 Patent—

1. A toy wagon, comprising a wagon-bed

having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, and a front seat resting on top of the said front and fitting between the said longitudinal seats and the said front seat-back.

2. A toy wagon, comprising a wagon-bed having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, a front seat resting on top of the said front and fitting between the said longitudinal seats and the said front seat-back, and vertical removable dowels engaging the said seat-back sections and the said tenons.

3. A toy wagon, comprising a wagon-bed having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, a front seat resting on top of the said front and fitting between the said longitudinal seats and the said front seat-back, and longitudinal removable dowels engaging the said front seat-back and the said front seat.

4. A toy wagon, comprising a wagon-bed having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, a front seat resting on top of

the said front and fitting between the said longitudinal seats and the said front seat-back, rear end pieces resting on the rear ends of the said longitudinal seats, having tenon-and-mortise connections with the said longitudinal seat-backs, and removable dowel-pins engaging the said longitudinal seat-backs and the tenons of the rear end pieces.

5. A toy wagon, comprising a wagon-bed having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, a front seat resting on top of the said front and fitting between the said longitudinal seats and the said front seat-back, a foot-rest and bolts for removably securing the foot-rest to the said front.

6. A toy wagon, comprising a wagon-bed having a bottom, a front, a rear end, sides, each made in sections of which the upper sections form seat-backs, longitudinal seats interposed between the side sections and resting on the said front and rear, the parts enumerated having registering apertures, bolts engaging the said apertures for fastening the parts together and allowing their dismemberment, a front seat-back extending over the said longitudinal seats, having tenons engaging mortises in the seat-back sections of the said sides, a front seat resting on top of the said front and fitting between the said longitudinal seats and the said front seat-back, a sectional step and bolts for removably securing the step to the said bottom and rear end.

7. A toy wagon, comprising a sectional wagon-body made in sections, rear longitudinal bolsters each made in sections, bolted to the bottom of the wagon-body, a rear axle, bolts connecting the axle to the said bolsters and to the said bottom, rear wheels removably held on the said axle, transverse front beams, a plate and bolts for fastening the plate to the beams and the latter to the said bottom, a front bolster bolted to the said plate, a front axle, a king-bolt engaging the said front axle, the said bolster and plate, and front wheels removably held on the said front axle.

8. A toy wagon, comprising a sectional wagon-body made in sections, rear longitudinal bolsters each made in sections, bolted to the bottom of the wagon-body, a rear axle, bolts connecting the axle to the said bolsters and to the said bottom, rear wheels removably held on the said axle, transverse front

beams, a plate and bolts for fastening the plate to the beams and the latter to the said bottom, a front bolster bolted to the said plate, a front axle, a king-bolt engaging the said front axle, the said bolster and plate, front wheels removably held on the said front axle, and a reach engaging the said king-bolt and bolted to the said bottom.

In testimony whereof I have signed my name to this specification in the presence of ¹⁰ two subscribing witnesses.

EDWARD C. SEEREITER.
